UNITED STATES PATENT OFFICE.

DANIEL KELLOGG BAKER, OF CHICAGO, ILLINOIS, AND CHARLES H. GREEN, OF NEW YORK, ASSIGNORS TO THE NEW YORK BRASS COMPANY, OF NEW YORK, N. Y.

GAS-BURNER.

SPECIFICATION forming part of Letters Patent No. 412,694, dated October 8, 1889.

Application filed May 12, 1887. Serial No. 237,981. (No model.)

To all whom it may concern:

Be it known that we, DANIEL KELLOGG BAKER, of Chicago, in the county of Cook and State of Illinois, and CHARLES H. GREEN, of the city, county, and State of New York, assignors to the NEW YORK BRASS COMPANY, a corporation, have invented a certain new and useful Improvement in Gas-Burners, (never yet patented in any country;) and we do hereby declare that the following is a full, clear, and exact description of the invention, which will enable others skilled in the art to which it appertains to make and use the same.

Our invention consists in a mechanism so constructed and arranged as more completely to regulate the pressure and flow and greatly to increase the illuminating-power of gases, whether natural or manufactured, when used for the production of light.

In the attempts to use for illuminating purposes the natural gases it has been found that no ordinary burner produces a satisfactory light. Indeed, the distinguishing characteristic of the combustion of the natural hydro-carbon gases seems to be the production of intense heat. While they have largely taken the place of coal, coke, and other fuels in the smelting and working of metals, and in other processes of the arts and manufactures which require the greatest heat, yet for the purposes of illumination they have usually proved flickering and unsteady, and their combustion, while producing great heat, has usually afforded very little light.

Our invention is designed to obtain from the combustion of natural gases a light of great illuminating-power and of uniform steadiness and brilliancy.

The mechanical part of our invention is described as follows:

Figure 1 shows in perspective our completed invention, including the chimney, which may be longer or shorter, as may be desirable. Fig. 2 is a central vertical section of the same. Fig. 3 is a plan view of the device, looking from the top downward. Fig. 4 is a cross-section of the same, drawn at the dotted lines N N, Fig. 2. Fig. 5 is a central vertical section of the cap B. Fig. 6 is an

outline of the different parts of the cap last mentioned, showing the different proportions thereof.

Similar letters of reference designate corresponding parts in the several figures.

A is an elongated tube fastened at its lower extremity, in the usual manner, to an ordinary gas-pipe, and through which the gas is introduced to the apparatus. It opens into the funnel-shaped cap B, which tends to regulate and equalize the pressure of the current of gas, while at the same time subjecting it to the heat of the flame. This cap connects the tube A with a tube C, surrounding it, and which conveys the gas from the cap B through two or more hollow projecting arms D D D, fixed in the frame, as shown in Fig. 4, into the reservoir or chamber E E. This reservoir or chamber E E has between its exterior and interior walls wire screens to further regulate and equalize the pressure and flow of the gas during its passage to the perforations at the top of the reservoir or chamber E E, where it is ignited. The reservoir or chamber E E may be constructed much larger than the proportions of the drawings indicate, so as to increase the steadiness of the flow of gas.

F is the cone, which surrounds the reservoir or chamber E E. It is beveled at the top and perforated at the side or at the side and top. It has on its outer side the shoulder G, on which the chimney rests, and by which it is in part held in place. It has within it, at the bottom, the perforated shell or screen H, and at or near its top the perforated screen M, which are designed to admit the air to the flame and regulate the same.

I is the chimney, designed for use in connection with the burner, and which is held in place by the shoulder G and the exterior gallery K K, as shown in Figs. 1 and 2.

One or more wire screens L L are placed between the pipe C C and the reservoir or chamber E E, and serve further to regulate the air and the flame.

What we claim as our invention, and desire to secure by Letters Patent, is—

In a gas-burner, the tube C, having the hol-

low laterally-projecting arms D, the funnel-shaped cap B, secured to the top of the tube C, and the annular reservoir or chamber E, having top perforations, said chamber surrounding a portion of the tube C and communicating therewith through the medium of the hollow arms D, combined with the supply-tube A, extending upward within the tube C and opening into the cap B, wire screens located within the chamber E between its top and the points of connection with the arms D, the perforated cone F, surrounding the

chamber E, and the perforated screens H and M, surrounding, respectively, the top and bottom of the chamber E, for the purpose specified.

DANIEL KELLOGG BAKER.
CHARLES H. GREEN.
